UNITED STATES PATENT OFFICE.

THORDORE H. WITTLIFF AND CHARLES W. PARKER, OF DAYTON, OHIO, ASSIGNEES, BY
DIRECT AND MESNE ASSIGNMENTS, TO FANNIE M. WITTLIFF, OF WACO TEXAS.

LIFTING-JACK.

1,203,673.

Specification of Letters Patent.

Patented Nov. 7, 1916.

Application filed October 22, 1914. Serial No. 867,936.

To all whom it may concern:

Be it known that we, THORDORE H. WITTLIFF and CHARLES W. PARKER, citizens of the United States, residing at Dayton, in 5 the county of Montgomery and State of Ohio, have invented certain new and useful Improvements in Lifting-Jacks; and we do declare the following to be a full, clear, and exact description of the invention, such as 10 will enable others skilled in the art to which it appertains to make and use the same, reference being had to the accompanying drawings, and to the letters and figures of reference marked thereon, which form a part 15 of this specification.

This invention relates to new and useful improvements in lifting jacks of a type especially adapted to be used in connection with 20 automobiles.

20 The jack of the present invention is of the screw type and the object of the invention is to provide a simplified form of jack which is of the requisite strength, efficient in operation and comprises a minimum number of 25 parts, as hereinafter more particularly described.

Referring to the accompanying drawings, Figure 1 is a side elevation of the improved jack with part of the standard broken away; 30 Fig. 2 is a section on the line *a—a* of Fig. 1; Fig. 3 is a section on the line *b—b* of Fig. 1; Fig. 4 is a section on the line *b—b* of Fig. 1 with the parts in a different position from that shown in Fig. 3; and Fig. 5 is a perspective view of the pawl lever for operating 35 the jack.

In the specification and drawings, similar reference characters indicate corresponding parts.

40 Referring more particularly to the drawings, 1 represents a base from which upwardly extends a hollow standard 2. The standard 2 is suitably braced to the base 1 by webs 3. Mounted and adapted to reciprocate within the hollow standard 2 is a screw 4 having a cap 5 adapted to engage the object to be elevated. The screw 4 and cap 5 are elevated by means of a ratchet nut 6 which surrounds the screw 4 and rests upon 45 the upper end of the standard 2. By rotating the ratchet nut 6 the screw 4 is elevated and lowered. The ratchet nut 6 is rotated 50

by the pawl end 7 of a lever 8 and said pawl end 7 is held in alinement with the ratchet nut 6 by a socket 9 provided with loops 10 55 which surround the hub 11 of the ratchet nut 6. The socket 9 rotates freely around the ratchet nut 6. The pawl end 7 of the lever 8 is suitably chamfered to permit the pawl end 7 to engage the teeth of the ratchet 60 nut 6 when the pawl end 7 is moved in one direction but to ride over the ratchet teeth when the pawl end 7 is moved in the opposite direction. The direction in which the nut 6 is rotated and, consequently, the direction 65 in which the screw 4 and cap 5 move depends upon the position in which the pawl end 7 is inserted in the socket 9. In Fig. 3, the pawl end 7 is inserted in the socket in a position to move the screw 4 up when the lever 70 8 is oscillated, while in Fig. 4, the pawl end 7 is reversed to rotate the ratchet nut 6 in a reverse direction to move the screw 4 down. The end of the lever 8 is provided with suitable indications "Up" and "Down" to indicate 75 to the operator in which position he should place the pawl end of said lever to move the screw 4. The screw 4 is prevented from rotation during the rotation of the nut 6 by a transverse pin 12 mounted in the 80 lower end of the screw 4. The ends of the pin 12 ride in grooves 13 along the inside of the standard 2. The said pin 12 is inserted in the screw 4 through an opening 14 at the top of one of the grooves 13.

85 The jack is actuated by oscillating the lever 8 meanwhile exerting a slight inward pressure upon the lever 8 to insure the pawl end 7 engaging the teeth of the ratchet nut 6.

Having described our invention, we claim. 90

1. A lifting jack comprising a hollow standard having internal grooves in opposite walls, the standard being provided with an opening which intersects one of said grooves, a lifting bar movable in the standard, and a pin extending transversely of the lifting bar and operating at its ends in said grooves, said pin being adapted to pass through the opening of the standard and to be held against movement on the lifting bar 95 by the bottom walls of the grooves.

2. A lifting jack comprising a standard, a lifting bar movable in the standard and having a screw formed thereon, a ratchet

nut engaging said screw, a member mounted to turn relatively to the nut and having a non-circular socket, and a lever having a beveled end and a non-circular portion to fit in said socket so that the beveled end will engage the ratchet nut in either of two positions.

Copies of this patent may be obtained for five cents each, by addressing the "Commissioner of Patents, Washington, D. C."

In testimony whereof we affix our signatures, in presence of two witnesses.

THORDORE H. WITLIFF.
CHARLES W. PARKER.
